UNITED STATES PATENT OFFICE.

JAMES W. HICKS, OF EVERSON, PENNSYLVANIA.

SWITCH-SIGNAL.

No. 823,726.

Specification of Letters Patent.

Patented June 19, 1906.

Application filed March 22, 1906. Serial No. 307,436.

To all whom it may concern:

Be it known that I, JAMES W. HICKS, a citizen of the United States, residing at Everson, in the county of Fayette, State of Pennsylvania, have invented certain new and useful Improvements in Switch-Signals; and I do hereby declare the following to be a full, clear, and exact description of the invention, such as will enable others skilled in the art to 5 which it appertains to make and use the same.

This invention relates to signals, and more particularly to railway-switch signals, and has for its object to provide a signal-lamp for switches which will be so arranged that it 15 may be filled and otherwise tended from the ground without the necessity of climbing the supporting-pole of the lamp.

Another object is to provide a lamp embodying these features which will be arranged 20 to swing so that it may maintain an upright position when lowered and which will be provided with means for shifting it to indicate the condition of the switch when the latter is thrown.

25 Other objects and advantages will be apparent from the following description:

In the drawings forming a portion of this specification, and in which like numerals of reference indicate similar parts in the several 30 views, Figure 1 is an elevational view of the signal with the lamp in raised position. Fig. 2 is a view similar to Fig. 1, showing the lamp lowered. Fig. 3 is an enlarged vertical section of the rod, showing its connection with the upright and with the shifting mechanism. Fig. 4 is a horizontal section on line 4-4 of Fig. 1, showing the shifting mechanism in top plan. Fig. 5 is an enlarged detail view of the lamp, a portion of the latter being broken 35 away to show the engagement of a bar therein.

Referring now to the drawings, the present invention comprises an upright 5, having a plurality of divergent supporting-legs 6, to which there is secured a horizontal plate 7, 45 this plate being thus located within the enclosure of the legs. The upper end of the upright 5 is turned laterally at right angles, as shown at 8, and is cylindrical, as shown, for introduction into a circular collar 9, which 50 extends laterally from the vertical sleeve 10.

This sleeve is engaged with the reduced central portion 11 of a rod 12, and the reduced portion 11 is somewhat longer than the sleeve 10, so as to permit of both sliding and rotary 55 movement of the rod in the sleeve. By reason of the engagement of the end 8 of the up-

right in the collar 9 the sleeve and rod are movable pivotally in a vertical plane with respect to the upright, and set-screws 13 are engaged in the collar and extend into a circumscribing groove 14, formed in the laterally-turned end of the upright to prevent disengagement of the collar from this end, and it will be understood that the set-screws may be operated to impinge against the angular 65 end of the upright, thus holding the sleeve and rod stationary with respect to the upright. A set-screw 15 is engaged in the sleeve 10 for operation to hold the rod against movement therein. 70

A yoke 16 is carried by the upper end of the rod and has a signal-lamp 17 mounted between its vertically-extending arm 16' for swinging movement upon a horizontal axis. This lamp is arranged to display two colors, 75 as shown at 18 and 19, as is usual, and, as will be seen, the rod 12 may be revolved in the sleeve 10 to give the desired signal to trains upon the track. The rod 12 has a longitudinally-extending passage 20 formed therethrough which is angular in cross-section, and slidably engaged in this passage and projecting beyond the ends of the rod there is a cross-sectionally angular bar 21. This bar at its upper end extends into an opening 22 in 80 the bottom of the lamp 17, which holds the lamp against pivotal movement in the yoke, and at its lower end the bar 21 lies normally within an angular socket 23, formed in the upper end of a socket-piece 24, which is revolvably mounted for vertical position in the plate 7. A laterally-extending lever 25 is carried by the socket-piece 24 and is connected by means of a link 26 with the switch-throwing mechanism 27 of a track 28. As 85 will be seen, the arrangement is thus such that when the switch is thrown the position of the lamp 16 will be changed and the signal thus altered to indicate the position of the switch. Diametrically opposite longitudinal 90 recesses 29 are formed in the inner surface of the rod 12 and laterally-extending lugs 30, carried by the bar 21, extend into these recesses, the longitudinal movement of the bar with respect to the rod being thus limited. 95

As will be apparent from the drawings, the arrangement is thus such that the rod 12 may be raised with respect to the sleeve 10 and for a certain distance with respect to the bar 21, 100 this movement of the rod with respect to the bar being sufficient to bring the bar out of en-

gagement with the lamp 17, so that the latter is free to move upon its pivot. Further vertical movement of the rod will bring the lower end of the recesses 29 into engagement 5 with the lugs 30, and the bar 21 may then be raised, with the rod, to bring the lower end of the bar out of the socket 23, thus permitting movement of the sleeve revolvably upon the laterally-turned end of the upright 5, so that 10 the upper end of the rod 12, with the lamp, may be lowered, the pivotal mounting of the lamp permitting it to maintain an upright position during this downward movement. The method of returning the lamp to its 15 operative position will be readily understood without further description, and it will be understood that the rod may be held against movement to lower the lamp by the set-screws 13, as described above.

20 What is claimed is—

1. A signal comprising a support, a vertical rod pivoted upon the support, a signaling device carried by the upper end of the rod, said rod being movable to bring the signaling device within reach of the ground, said rod being movable to shift the signaling device into different signaling positions, and means engaged with the lower end of the rod for shifting the rod, said rod being movable slidably 25 out of engagement with the shifting means to permit of downward movement of the upper end of the rod.
2. A signal comprising a support, a vertical rod pivoted upon the support for downward movement of its upper end, a lamp piv- 30

otally mounted upon the upper end of the rod for movement upon a horizontal axis to maintain a vertical position at all times, and means for holding the lamp against movement with respect to the rod when the latter is in vertical position, said rod being movable to bring the holding means out of operative position. 40

3. A signal comprising a support, a vertical member pivoted upon the support for movement of its upper end toward the ground, 45 a lamp pivotally mounted upon the upper end of the member for swinging movement upon a horizontal axis, said rod having a cross-sectionally-angular passage formed longitudinally therethrough, a revoluble socket-piece 50 mounted vertically at the lower end of the rod, a bar fitted within the passage of the rod for sliding movement therewithin, said bar being engaged at its upper end in the lamp and at its lower end in the socket-piece for rotation of itself and the rod with the socket-piece, and means for rotating the socket-piece, said rod being movable vertically independently of the bar to bring the latter out of engagement with the lamp, said 55 bar being constructed and arranged for subsequent vertical movement with the rod to bring the bar out of engagement with the socket-piece. 60

In testimony whereof I affix my signature 65 in presence of two witnesses.

JAMES W. HICKS.
